UNITED STATES PATENT OFFICE

MAURICE N. TRAINER, OF EAST ORANGE, NEW JERSEY, ASSIGNOR TO THE AMERICAN BRAKE SHOE AND FOUNDRY COMPANY, OF WILMINGTON, DELAWARE, A CORPORATION OF DELAWARE

BRAKE SHOE

Application filed May 31, 1930. Serial No. 457,794.

This invention relates to brake shoes and it has for its object to reenforce and strengthen the shoe and to enable the shoe to be continued in use and give efficient service even though cast iron parts may be fractured.

A car shoe having a cast iron body with or without inserts in the face thereof and with a ductile metal reenforce back embedded therein will fracture through the body in service but the parts will be held together by the metal back until it breaks so that the shoe may be continued in use and give efficient service. The fracture in the body ordinarily occurs transversely and at one side of the attaching lug. Since the life of a freight car shoe averages four to five years and during service is subjected to a variety of stresses and strains, vibrations and pressures, it cannot be determined with any degree of certainty whether or not the back will break before the body is worn down to the limit of wear. Shoes have been found with the body and the back broken after very little wear and even when the shoe is practically new, and then again shoes have been taken off the heads worn down to and even below the limit of wear with the body fractured but the back still in serviceable condition. It is found, however, that the fracture usually occurs in the body at one or the other side of the attaching lug and close thereto, and my invention has for its object to reenforce and strengthen the back in particular and the shoe generally at the middle portion of the back to withstand the forces which tend to break the back after the body is fractured at or about midway between its ends.

And another object is to anchor the attaching lug strap securely to the back of the shoe to prevent it from being torn loose from the shoe body in service and permitting the body to fall away from the head.

I have illustrated the invention in a common cast iron car shoe having a steel reenforce back and referring thereto,

Fig. 1 is a plan view of the back and lug strap with the cast iron body shown in broken lines.

Fig. 2 is a longitudinal sectional view of the shoe on the line 2—2 of Fig. 1.

Fig. 3 is a perspective view of the lug strap.

Fig. 4 is a transverse sectional view on the line 4—4 of Fig. 2.

Fig. 5 is a detail sectional view through the back and lug strap on the line 5—5 of Fig. 1.

Fig. 6 is a sectional view of the back on the line 6—6 of Fig. 1.

Referring to the drawing, 7 is the cast iron body of the shoe and 8 is ductile metal back which is embedded in the body at the back thereof during the casting operation. The lug strap 9 has legs 10 and elongated wings 11 and the side edges of the reenforce back are cut out at 12 to receive the legs 10, the wings 11 being located beneath the back and extend longitudinally thereof. These wings overlap the middle portion of the shoe body at or about which fracture is most likely to occur. The back is embedded securely and rigidly in the body during the casting operation and it is most likely to break opposite the fracture in the body. The cut-outs in the side edges of the back reduce the strength of the back to resist stresses, strains and vibrations to which the back is subjected in service after the body is fractured. The wings provide sufficient reenforcement for the back at that part which is weakened by the cut-outs and where the stresses, strains and vibrations will most seriously affect the back after the body is fractured, to overcome these weaknesses in the back and enable the shoe to continue in efficient service until it is worn out.

The body metal is run up at 12 at the sides of the legs of the lug strap to form with the strap the attaching lug of the shoe. The wings are welded at 13 to the back. The elongated wings welded to the underside of the back securely anchor the lug strap to the back and through the back to the body of the shoe. The projections 12, 12 not only protect the lug strap against distortion in shipping and in service but they also reenforce and strengthen the strap to provide a strong and substantial attaching lug. Sometimes the projections 12, 12 are fractured and dislodged from the shoe and in such case the lug strap

may be disengaged from the shoe. The elongated wings 11, 11 provide a secure anchorage for the lug strap in the shoe beneath the back so that it will not be disengaged even though the projections 12, 12 are broken away. The lug strap is preferably made from a single sheet of metal bent to shape and in the complete shoe those parts of the wings which project beyond the strap 9 will interlock with the back and with the body to secure the strap in place with or without the projections 12, 12.

I have shown the invention embodied in a common cast iron car shoe but it is adaptable for shoes of other types and I reserve the right to make any changes necessary or desirable in adapting the invention to brake shoes of different kinds and for other purposes within the scope of the following claim.

I claim:

A brake shoe comprising a body, a continuous reenforce back embedded in the body throughout its length, and a lug strap, said back having oppositely disposed cut-outs in its side edges, and said lug strap being separate from the back and having legs engaged with said cut-outs, the body metal being extended through said cut-outs and alongside said legs, and wings forming part of the lug strap and projecting inwardly from the ends of said legs, said wings extending longitudinally of the back and against the inner face thereof and secured rigidly to the back to reenforce that portion of the back where it is reduced in cross-section by the cut-outs.
